UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

FURNACE

Original application filed September 26, 1921, Serial No. 503,241. Divided and this application filed April 4, 1930. Serial No. 441,543.

This invention relates to a new and improved open hearth furnace, and more particularly to a construction adapted to so direct the entering gases and air in an open hearth furnace as to produce a quick burning and intensely hot flame adapted to provide working heat adjacent the full surface of the metal in the furnace, and further adapted to provide a large port area through which to 10 exhaust the products of combustion.

This application is a division of my co-pending application Serial No. 503,241 filed September 26, 1921.

My invention comprises an improvement 15 in that portion of an open hearth furnace between the ports and the bath or melting chamber, and the remainder of the furnace and its appurtenances may be of any usual construction. As is well known in open 20 hearth practice, the furnace is double-ended and reversible, and is provided at each end with gas or air ports which serve upon the outgoing end to carry off the products of combustion. In certain types of these furnaces burning producer or like gases, these 25 incoming gases are passed through regenerative chambers and are thus preheated. The incoming air is preheated in a similar manner and the heat of the furnace flame is correspondingly increased. It is highly desirable 30 in such furnaces to provide a short, quick flame which is directed toward the metal in the bath and which does not extend to the outgoing end of the furnace. However, 35 ever, in actual practice, since the same ports serve both to introduce the air and gas and to carry off the products of combustion, the latter function has been largely the determining factor as regards the size of ports. This 40 is for the reason that the products of combustion are of considerably greater volume than the incoming air and gas.

To secure a short, quick flame, it is essential 45 that there be a quick and thorough mixture of the incoming air and gas. It is impractical to secure such a mixture and flame when the air and gas ports are of the usual comparatively large area. Endeavors are made to secure this quick mixture with such 50 ports by surrounding the gas stream upon its

sides and top with the air stream. However, the intermixture in general occurs gradually as the gas is passed across the furnace, the lighter gas gradually rising and intermingling with the heavy air, combustion thus 55 gradually taking place.

Endeavors have been made to secure a quick mixture and short flame by means of using comparatively small air and gas ports and providing auxiliary ports for carrying 60 off the products of combustion, for example, as shown in the patent to Frank B. McKune, No. 1,339,855, issued May 11, 1920. In such constructions dampers are provided to close the auxiliary passages upon the incoming end 65 of the furnace. The addition of auxiliary ports and uptakes unduly complicates the structure and this is particularly true in the usual type of furnace burning producer or similar gases. In such furnaces, as generally 70 constructed, a single gas uptake and port is flanked by an air uptake and port upon each side thereof. All these ports are essential to the operation of a furnace upon the incoming end, although as has been stated, the port 75 area is increased over that necessary for the incoming air and gas in order to be of a size adequate to take care of the products of combustion.

It is an object of the present invention 80 to provide means located intermediate the ports and the furnace chamber which means are adapted to vary the effective passage area between the ports and chamber.

It is a further object to provide means of 85 this character which are adjustable to provide the full port area for handling the products of combustion.

It is an additional object to provide means which may be readily installed without undue 90 modification of the existing furnace structure.

It is also an object to provide a device which is relatively simple in design, construction and operation.

Other and further objects will appear as the description proceeds.

Broadly my invention comprises the interposition of dampers between the ports and furnace chamber, these dampers being ad- 100

justable to vary the effective passage area. I have illustrated a preferred embodiment of my invention in the accompanying drawing, in which—

5 Figure 1 is a fragmentary, longitudinal section of an open hearth furnace having my invention applied thereto; and

Figure 2 is a horizontal section of the form of construction shown in Figure 1.

10 The form of construction shown in the drawing comprises the gas uptake 81 terminating in the gas port 82. The air uptakes 83 are located upon either side of the gas uptake and meet at 84 above that uptake. Offsets are formed in the lateral walls of the furnace adjacent the air uptakes and water-cooled hinge plates 85 are located in these offsets. The water-cooled dampers 86 are swung upon these hinges and are adapted to be swung to a position such as that shown in 20 Figure 2 to direct the incoming air inwardly against the incoming gas. Upon the outgoing end of the furnace, the dampers are swung outwardly parallel with the furnace wall and they thus permit the full area of the 25 ports to be effective in carrying off the products of combustion.

The form of construction which I have shown serves to restrict the effective passage 30 area between the ports and the furnace upon the incoming end of the furnace. It thus causes a quick mingling of air and gas and a short flame upon the incoming end and further permits the ready discharge of the products of combustion through the full port 35 area. Modifications of my construction may be made and it is my intention to cover all variations coming within the spirit and scope of the appended claims.

40 I claim:

1. In an open hearth furnace, the combination of regenerating chambers adapted to be connected alternately to an air supply and to a stack, a heating chamber, passages connecting said chamber with the respective regenerating chambers, gates or valves pivotally mounted in said passages, the pivotal shafts being arranged on opposite sides of the passages, means for swinging said valves 45 or gate towards and from each other to change the cross sectional areas of the passages and means for introducing gas into the passages at points anterior to the gates or valves.

2. An end construction for regenerative 55 open hearth furnaces having a throat for the passage of fuel to the hearth or for the escape of products of combustion, and means for varying the effective area of the throat including a damper movable into the throat 60 from the side.

3. An end construction for regenerative open hearth furnaces having a throat for the passage of fuel to the hearth or for the escape of products of combustion, and means 65 for varying the effective area of the throat

including a damper pivotally supported at the side of the furnace and adapted to be swung into and out of the throat.

4. An end construction for regenerative open hearth furnaces having a throat for the passage of fuel to the hearth or for the escape of products of combustion, and means for varying the effective area of the throat including two dampers, one on each side of the throat and being movable horizontally into 70 the throat.

5. An end construction for regenerative open hearth furnaces having a throat at the end of the hearth, means for delivering gas centrally to the throat, means for delivering air to the throat to each side of the gas supplied, and dampers horizontally movable into and out of the throat for varying its effective area, the damper converging toward the hearth to direct the incoming air toward 80 the stream of incoming gas.

6. In a regenerative reversing furnace, a combustion and an exhaust port, a damper pivotally mounted at one end in the port, and means for moving the damper to vary the 90 area of the port.

Signed at Chicago, Illinois, this 1st day of April, 1930.
